UNITED STATES PATENT OFFICE.

EDWIN F. STRANGE, OF TAUNTON, MASSACHUSETTS, ASSIGNOR OF ONE-HALF
TO ELIAS W. STRANGE, OF SAME PLACE.

TRUCK.

SPECIFICATION forming part of Letters Patent No. 401,470, dated April 16, 1889.

Application filed July 11, 1888. Serial No. 279,683. (No model.)

To all whom it may concern:

Be it known that I, EDWIN F. STRANGE, of Taunton, in the county of Bristol and State of Massachusetts, have invented a new and useful Improvement in Brick-Yard Trucks, which will, in connection with the accompanying drawings, be hereinafter fully described, and specifically defined in the appended claims.

In said drawings, Figure 1 is a top plan view of a truck embodying my invention. Fig. 2 is a side elevation of the same. Fig. 3 is a vertical section taken through the axle, wheels, and springs transversely to the longitudinal line of the truck. Fig. 4 is a vertical section taken transversely to the axle through the lineal center thereof, and viewed as from the left in Fig. 3, certain parts being shown in section. Fig. 5 is a vertical section taken transversely to the axle, as on line Z Z, Fig. 3, and viewed as from the left in that figure, certain parts being shown in elevation.

This invention relates more especially to that class of trucks which are employed in brick-yards for transporting the brick from point to point therein during the various processes and stages of their manufacture; and it consists in features of novelty herein-after particularly described, and pointed out in the claims.

Referring again to the drawings, A A represent the wheels, which, in view of their exposure to great changes of temperature and degrees of moisture and dryness, are preferably formed entirely of iron, as an integral casting, with the exception of the axle-boxes, to be hereinafter explained.

The axle B consists of three several and separable parts—to wit, a central casting, embodying the tubular ends a a, united by bars b b, and the wrought-metal journals c c, held in place in tubes a by set-screws d. Near each end of journals c, I form a transverse hole, e, in which to insert the "linchpins" f, that secure wheels A upon said journals. The journal-boxes g in hubs n of the wheels are formed with an external reduction at their middle portion, so that when inserted in hubs n a concentric oil-chamber, i, is formed, the oil being introduced into said chamber through passage k of the hub n, a plug-screw, l, closing said passage after the oil is introduced. The

oil is introduced between the interior wall of boxes g and journals c through a series of small passages, j, in the thin part of the boxes, as shown. Said hubs n are formed with an elongation or band, q, to extend inward over tubular portion a a sufficient distance to prevent dirt from entering boxes g, and upon the outer end of said hubs I secure by a set-screw, p, the well-fitting caps m, to exclude dust or dirt at that end of the boxes, yet allowing access to the linchpins f when desired.

Upon tubes a a, I form the lugs s, on which to seat the spring-blocks t, that receive springs C, as shown; and at the lineal center of the axle is formed the lug u, to which the draft bar or pole v is bolted, as shown, a supporting-prop, w, being hinged to said bar to support it at proper height, as also the forward end of body D, which at its front end rests on said bar, and at or near its lineal center rests upon spring-blocks x.

As the springs, body, and draft-bar constitute no part of my invention, and are only shown for purpose of illustrating the object of my invention, they need be no further described.

By forming the central portion of the axle separate from the journals many advantages are secured, among which are the facts that the central portion may be of common cast-iron, with the facility of forming, inexpensively, the described lugs to receive the spring-blocks and draft-bar, as also the tubes a, for insertion of the journals, and when said journals have become worn so as to be unfit for further service they can be readily replaced with new. By forming said journals of requisite length, and with holes f at both ends, they can, after the outer end has been worn beyond fitness for use, be reversed, and the end that is so worn can be secured in tube a, and the other end (not before worn) subjected to use as the bearing for the wheel, thus obtaining double service from the journals, and by forming boxes g separate and removable from the hubs I can not only provide the described oil-chamber i with its capacity for oiling the wheels, but when worn past use the boxes are readily replaced, thus rendering wheels A durable far beyond what has been hitherto possible.

I claim as my invention—

1. A truck-axle formed with an integral cast-metal center having tubes *a a*, united by a bar or bars, *b*, with the insertible journals *c c*, removably secured in said tubes, substantially as specified.
2. A truck-axle formed with the integral cast-metal center having tubes *a a* for the reception of journals *c c*, and the lugs *s*, formed at each end to support the springs, substantially as specified.
3. A truck-axle formed with the integral cast-metal center having tubes *a a*, to receive journals *c c*, and a lug, *u*, for connection of the draft-bar, substantially as specified.
4. A truck-axle consisting of a unitary cast-metal center having lug *u* for the draft-bar, lugs *s* for the springs, and tubes *a* for the journals *c*, and said journals therein arranged, all substantially as specified.
5. The combination, with the cast-metal center of a truck-axle having tubes *a*, of the cylindrical journals *c*, secured in said tubes by set-screws *d*, and formed to be reversed for double duty, as specified.
6. The combination, with wheels *A*, having metal hubs provided with oil-passages *k*, and the supporting-journals, of boxes *g*, insertible in and removable from said hubs and formed with a chamber or recess, *i*, and perforations *j*, leading from said recess *i* to the journals, substantially as specified.

EDWIN F. STRANGE.
